INVENTOR

George W. McGill

UNITED STATES PATENT OFFICE.

GEORGE W. MCGILL, OF RIVERDALE, NEW YORK.

BUTTON-FASTENING FOR GARMENTS.

SPECIFICATION forming part of Letters Patent No. 716,267, dated December 16, 1902.

Application filed May 13, 1902. Serial No. 107,096. (No model.)

To all whom it may concern:

Be it known that I, GEORGE W. MCGILL, a citizen of the United States, and a resident of Riverdale, in the county of New York, and State of New York, have invented certain new and useful Improvements in Button-Fastenings for Garments, of which the following is a specification.

My invention relates to an improved mode of securely attaching ordinary buttons to fabrics by metallic fastenings, and has for its object securing such attachment without impairing the desirable swivel and flexible character provided such connection when the button is fastened or attached to the garment in the ordinary manner with thread by sewing.

In the accompanying drawings, making part of this specification, and in which similar letters and numerals of reference indicate corresponding parts, Figure 1 is a transverse sectional view of an ordinary bar-button. Fig. 2 is a plan view of a band or strap of leather or other flexible material folded in upon itself longitudinally at its center part.

Fig. 3 is a top view in perspective of a metal collar or case. Fig. 4 is a perspective view of a clamping-disk or packing-plate. Fig. 5 is a view in perspective of the under side of a base-plate. Fig. 6 is a transverse sectional elevation of the button proper and its attaching member connected together as intended. Fig. 7 is a perspective view of a washer or riveting-bur used in connection with the riveting-stem of the attaching member of the device. Fig. 8 is a side elevation of the completed device attached to a fabric. Fig. 9 is a perspective view of a modified construction of the button-eye-engaging link, made of metal. Fig. 10 is a side elevation of the button proper provided with a looped eye linked to the fastening member by the modified link shown in Fig. 9, the fastening member being shown in transverse section. Fig. 11 is a view similar to Fig. 10, showing a modified construction of the attaching member of the device and the under portion of the button proper. Fig. 12 is a view in perspective of the modified construction of the button-eye-engaging link shown in Fig. 9 spread open in the position it occupies when in use, as is shown in Figs. 10, 11, and 13; and Fig. 13

shows a still further modified construction of the button-eye with the link fashioned as shown in Fig. 12 in riding engagement therewith.

55

Fig. 1 represents in cross-section an ordinary bar-button, the button proper being marked A, its eyear marked 1, and the open part of its eye marked 2.

Fig. 2 represents a band B, of leather, tape, 60 or other flexible material, folded longitudinally at its center 3, doubling the material in that part.

Fig. 3 is a top view in perspective of a metallic plate or collar C, having a beaded central opening or eye 5 and dependent rim 6.

Fig. 4 is a perspective view of the under side of a clamping disk or plate D, having part of the opposite sides of its periphery serrated, as at 7 7, and parts of its inner surface provided with pointed projections 8.

Fig. 5 is a perspective view of the under surface of a clamping and riveting base-plate E, provided with a central tubular riveting-pillar 9.

75

One end of the flexible band B is passed up and down through the button-eye 2 in manner to bring its center 3 across the eyear 1. The ends of the band are then passed down through the opening 5 in the collar C, and the 80 band is spread open in the cupped under side of such collar. The intermediate clamping-plate D is now inserted in the cup of the collar in manner to bring its smooth surface to bear against the open spread of the band B and 85 cause the serrated sections of its periphery to engage the band at its folds 11 11. The ends 4 4 of the band B are now folded over toward each other upon the under surface of the clamping-plate and pressed upon its pointed 90 projections 8 8, as indicated by the dotted lines in Fig. 4. The clamping and riveting base-plate E is now inserted in the collar C, with its riveting-pillar 9 pointing outward, and is pressed up therein while the rim of the 95 collar is being upset or flanged over the periphery of such plate, securing the parts together, and clamping the band B in the fastening member between the inner surface of such collar, both surfaces of the intermediate 100 plate D, and the inner surface of the base-plate E, completing the device as it is before

its attachment to a fabric and as it is shown in the sectional Fig. 6, wherein the parts are shown thus assembled.

In attaching the device to a fabric an opening is made in the latter sufficient to admit the free end of the tubular pillar 9 of the base-plate, and after said end is passed through the fabric the bur G (shown in Fig. 7) is placed upon it, and the end is then upset upon the outer surface of such bur, clamping the fabric between the inner surface of such bur and the outer surface of the base-plate, and securing the device to the fabric, as shown in Fig. 8, which is a side elevation of the completed device attached to a fabric, the latter (marked 10) being shown in section. In attaching the device to leather and such like heavy material the riveting tubular pillar 9 of the bed-plate may be upset direct upon the same without the bur G intervening.

Figs. 9, 10, 11, 12, and 13 show alternate construction of some of the parts, Fig. 9 being a side elevation in perspective of a wire link forming a substitute for the band B and having its looped center 3' left round and its ends 4' flattened, and Fig. 10 shows the link B' so formed entered in a button-eye 1' and having its ends 4' entered, folded apart, and secured in the fastening member of the device, the latter being shown in section. Where the link connecting the button with the fastening member is made of metal or of thick flexible material—such as leather, heavy tape, and such like—it will be found unnecessary to use the intermediate clamping-plate D, and also in many instances where the button-connecting link is made of thin fibrous or flexible material it will be found practicable to dispense with the use of such intermediate clamping-plate and use a paper wad instead to bear upon the ends of the flexible link in securing the same in the fastening member, or where it is an object to have the fastening member very thin neither intermediate plate nor wad need be used and the ends of the band forming such link may be folded upon themselves to increase their clamping bulk or be glued to the inner surface of the collar C and the base-plate E clamped direct upon them in accomplishing such end, and such base-plate may be provided with inwardly-pointing projections, similar to those shown at 8 in Fig. 4, to bear against and penetrate such flexible-link ends to further secure them therein. Fig. 11 is a view similar to Fig. 10, excepting that the rim of the base-plate is flanged upon the rim of the collar instead of the rim of the collar upon it, as shown in the other figures. Fig. 12 shows an open formation of the link B', made of wire, which may be used with a button having an elongated looped eye. The long eye 1" of the button is first passed down through the opening 5 in the collar of the fastening member and the open link entered therein, as shown in Fig. 13, in which the collar appears in transverse section. The but-

ton is then drawn up, bringing the parts 4' 4' of the link up against the inner top surface of the collar, where they are secured in the manner before described.

Where covered buttons are used in the device, its fastening member may be covered with similar material of similar color and in a similar manner and its button-connecting link provided of similar color and material, if suitable.

What I claim as my invention, and desire to secure by Letters Patent, is—

1. A button-fastening for garments consisting of a button proper and a button-attaching member, the button proper secured to such attaching member by an intermediate link, the ends of the material forming such link being permanently secured in such attaching member directly and without engaging the fabric of the garments to which the device is attached.

2. A button-fastening for garments consisting of a button proper and a button-attaching member, the button proper secured to the attaching member by means of a link connection, the central part of such link being linked with the eyebar of the button with the ends of such link permanently secured in such fastening member directly and without engaging the fabric of the garments to which the device is attached.

3. In a button - fastening for garments, a button proper provided with an attaching member to which it is inseparably connected by a non - integral and independent flexible link engaging the eye of the button intermediate said button and its attaching member and permanently secured to such member directly and without engaging the fabric of the garment to which the device is attached.

4. In a button - fastening for garments, a button proper provided with an independent metallic attaching member, the button proper secured to such independent metallic attaching member by a link composed of flexible material passed through the eye of such button and having its ends secured in such independent metallic attaching member directly and without engaging the fabric of the garments to which the device is attached.

5. In a button - fastening for garments, a button proper provided with an attaching member, the button proper secured to such attaching member by a flexible link the central part of which link is looped through the eye of the button and its end parts passed down through an opening in the cap of the fastening member wherein such end parts are spread apart and permanently secured by clamping them between the inner surfaces of the parts composing the fastening member.

6. In a button - fastening for garments, a fastening member consisting of a centrally-pierced upper plate providing a collar, and a lower plate forming a base, and having projecting through the central opening in such collar the fold of an inverted-U-shaped link

part engaging the eye of the button, and secured to such member by having its flat and turned-over ends clamped between the upper and lower plates of same.

5 7. In a button-fastening for garments the combination of a button A, an attaching member C, and an independent and intermediate link B, such link connecting together the button and the attaching member by having its 10 center part interlocking with the button-eye and its end parts secured internally in the attaching member directly and without engaging the fabric of the garments to which the device is attached.

15 8. In a button-fastening for garments an attaching member composed of a collar C, and a base-plate E, the top of such collar provided with a central opening 5, and the base-plate provided with a tubular riveting-pillar 9, in 20 combination with a button-connecting link B, secured in such attaching member and having its looped center 3 projecting out through the opening 5 in the top of such member.

9. In a button-fastening for garments, an 25 attaching member composed of a collar C, a clamping and riveting base-plate E, secured thereto, and an intermediate clamping-washer D, in combination with a button-connecting link made of flexible material and secured in 30 such fastening member with its looped center projecting out through the open center of the collar of such member.

10. In combination with a garment-button, a metallic attaching member to which such 35 button is secured in linked connection by means of a separate piece of material engaging centrally with the eye of the button and having its end parts secured to such attach-

ing member directly and without engaging the fabric to which the device is attached. 40

11. As a new article of manufacture a button-fastening for garments consisting of a button proper and a metallic attaching member, to which member the button is secured in link connection by means of a separate 45 piece of material engaging centrally with the button-eye, the end parts of such material being secured to such attaching member directly and without engaging the fabric to which the device is attached, a riveting-pillar 50 projecting from the outer base of such attaching member and a riveting-bur adapted to be secured upon the free end of such pillar in manner to clamp the fabric between the upper surface of such bur and the under 55 surface of the base of the attaching member.

12. As a new article of manufacture a button-fastening for garments and other fabrics consisting of a button proper connected to a metallic attaching member by means of an 60 intermediate flexible link engaging centrally with the eye of such button and having its end parts secured to such attaching member directly and without engaging the material of the garment or other fabric to which such 65 attaching member may be fastened, such attaching member having independent means for being secured to such fabric.

Signed at Riverdale, in the county of New York and State of New York, this 10th day 70 of May, A. D. 1902.

GEORGE W. MCGILL.
